(57) **CLAIM**

The ornamental design for a building block doll, as shown and described.

DESCRIPTION

FIG. 1 is the first embodiment of the front, right, and top perspective view of a building block doll, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is the second embodiment of the front, right, and top perspective view of a building block doll, showing my design.

FIG. 10 is a rear, left and bottom perspective view of the building block doll of FIG. 9.

FIG. 11 is a front elevation view of the building block doll of FIG. 9.

FIG. 12 is a rear elevation view of the building block doll of FIG. 9.

FIG. 13 is a left side elevation view of the building block doll of FIG. 9.

FIG. 14 is a right side elevation view of the building block doll of FIG. 9.

FIG. 15 is a top plan elevation view of the building block doll of FIG. 9; and,

FIG. 16 is a bottom plan elevation view of the building block doll of FIG. 9.

The broken lines depict portions of the building block doll that form no part of the claimed design.

1 Claim, 16 Drawing Sheets
